UNITED STATES PATENT OFFICE

123,529

DESIGN FOR A DRESS

Margaret Ellenbogen, New York, N. Y.

Application September 4, 1940, Serial No. 94,802

Term of patent 3½ years

To the Commissioner of Patents:

Be it known that I, Margaret Ellenbogen, a citizen of the United States, residing at 260 West End Avenue, New York city, in the county of New York, and State of New York, have invented a new, original, and ornamental Design for a Dress, of which the following is a specification, reference being had to the accompanying drawing, forming a part thereof.

The pocket and belt are embroidered with nailheads.

I claim:

The ornamental design for a dress, substantially as shown and described.

MARGARET ELLENBOGEN.
